UNITED STATES PATENT OFFICE.

MAURICE BRUNET, OF LIEGE, BELGIUM, ASSIGNOR TO MAISON DETILLEUX, SOCIÉTÉ ANONYME, OF LIEGE, BELGIUM.

STEAM ENGINE.

Application filed August 17, 1921. Serial No. 493,105.

To all whom it may concern:

Be it known that I, MAURICE BRUNET, a subject of the King of the Belgians, residing at Liege, Belgium, 84 Rue Sur-La-Fontaine, have invented certain Improvements in or Relating to Steam Engines, of which the following is a specification.

The present invention relates to improvements in or relating to steam engines of the compound type, and more particularly to a particular mechanism for the distribution of the steam through the valves, which comprises a device for the modification of the distribution allowing the use in the large cylinder of either live steam or steam evacuated from the small cylinder, according that a high power or a reduced power is required.

The improved valve-distribution mechanism according to the present invention is more particularly designed for use in compound system engines driven by high pressure steam produced for instance in an instantaneous vaporization generator, and the steam engine, embodying the said mechanism, which will be described hereunder by way of example therefore comprises some special arrangements, mainly in order to avoid the escape of steam of the joints of the piston rods with the bottoms of the cylinders, but it must be understood that the invention is in no way limited to engines using steam at very high pressures or comprising the said special arrangements.

In the accompanying drawings:

Fig. 1 is a vertical longitudinal section of a compound steam engine embodying the improvements forming the subject matter of the present invention.

Fig. 2 is partly a plan and partly a horizontal section of the said engine, said section being taken on the line 2—2 of Fig. 1.

Fig. 3 is a partial transverse section taken on the line 3—3 of Fig. 1.

Figs. 4, 5, 6 and 7 are vertical sections taken respectively on the lines 4—4, 5—5, 6—6, 7—7 of Fig. 3.

Fig. 8 is a horizontal section taken on the line 8—8 of Fig. 3.

Figs. 9 and 10 are diagrams indicating the path followed by the steam in the two conditions of working the engine.

Fig. 11 is a partial horizontal section taken on the line 11—11 of Fig. 1, and

Figs. 12 and 13 are cross sections taken

on the lines 12—12 and 13—13 of Fig. 11 respectively.

In the embodiment illustrated in the accompanying drawings, 1 and 2 are the superposed cylinders of each pair of cylinders, closed at the back by means of solid bottoms 3 and 4 and at the front by means of a hollow casting 5 which is bored in 6 and 7 to allow the passage of the piston rods 8 and 9.

In order to prevent any escape of steam, the said rods are provided with packings 10, and the pistons 11 and 12 in the cylinders are provided with packings 13.

At the front of the castings 5 the piston rods 8 and 9 pass through glands or stuffing boxes 14 and are secured at the end to a common cross-piece 15 sliding in slide-ways 16 solid with the castings 5. To the centre of the cross-piece 15 is pivotally connected the connecting rod 17 which transmits the motion of the pistons to the crank 18 of the crank shaft 19. The bearings 20 of the crank shaft are mounted in a crank shaft 21 forming an oil bath and to which the castings 5 are hermetically united.

The live steam is brought to each pair of cylinders by means of a pipe 28 and is distributed by means of a set of valves of which the axis are all arranged parallel to the axis of the cylinders, and which are mounted in a single casting 29 forming a solid block with the said cylinders. The set of valves comprises two admission valves 30 and 31 for the small cylinder, two exhaust valves 32 and 33 for this same small cylinder, two admission valves 34 and 35 for the large cylinder, two exhaust valves 36 and 37 also for this large cylinder, an auxiliary admission valve 38 permitting to send live steam to the admission valves of the large cylinder, an auxiliary exhaust valve 39 allowing to get the exhaust steam from the exhaust valves of the small cylinder to go directly to the atmosphere (or in some cases to a condenser), and finally a check valve 40 serving to prevent live steam brought to the admission valves of the large cylinder to reach the exhaust of the small cylinder.

The chambers or compartments containing the said valves are all placed on one side of the casting 29 and are closed by means of threaded stoppers 41 which may easily be removed for the inspection and the cleaning of the valves. All the valve rods 42

are directed towards the other side of the said casting 29 and are provided with series of circular grooves 43 to prevent the escape of steam where they pass in the bores 44 of 5 the casting 29; they are subjected to the action of closing springs 45 and their inner ends are adjustably connected to pushers 46, 47 and 48 which are guided in bushings suitably arranged in the crank shaft 10 21 (Figs. 1 and 2). Before describing the distribution mechanism which acts on the said pushers to open the various valves in the manner and in the order of succession required the connections of the valves 15 between themselves and with the cylinders, and then their operation will firstly be indicated.

The chambers 50, 51 and 52 containing the valves 30, 31 and 38 continuously receive 20 live steam supplied by the pipe 28; for this purpose they communicate between them by means of passages 53 in one of which the said pipe has its opening. The opening of the valve 30 allows the steam to pass in a 25 chamber 54 which is connected through a passage 55 to the back part of the small cylinder, and also through a passage 56 to the chamber 57 of the exhaust valve 32.

Just the same the opening of the valve 31 30 allows the steam to pass to a chamber 58 which is connected by means of a passage 59 to the front part of the small cylinder and also, by means of a passage 60 to the chamber 61 of the exhaust valve 33.

35 The lifting of one or the other of the valves 32, 33, allows the steam to pass in a passage 62 which leads to the chamber 63 of the valve 39, and when the latter valve is open it allows in its turn the steam to pass 40 in a passage 64 which leads to the atmosphere or in some cases to a condenser.

This same chamber 63 communicates by 45 means of a passage 65 with the valve 40 so that, when the latter is lifted, the exhaust steam of the small cylinder arrives in the corresponding chamber 66 and from there passes to the chambers 67 and 68 of the valves 34 and 35 by way of passages 69.

The valve 34 when opened allows the steam 50 to pass from the chamber 67 in a passage 70 which leads to the chamber 71 of the exhaust valve 36, which chamber also communicates by means of a passage 72 with the back part of the large cylinder. Similarly, 55 the valve 35 when opened allows steam to pass from the chamber 68 to a passage 73 which leads to the chamber 74 of the valve 37, which chamber also communicates with the front part of the large cylinder through 60 a passage 75.

The lifting of one or the other of the valves 36, 37, results in putting the respective chambers 71, 74 into communication with an exhaust duct 76 which leads to the 65 atmosphere. Finally when the auxiliary

valve 38 is open, the high pressure steam of the chamber 52 is allowed to pass through a passage 77 into the chamber 66 of the valve 40.

The operation of the valves is as follows: 70

1. Normal working with expansion of the steam successively in the two cylinders. The auxiliary admission valve 38 is kept closed, the auxiliary exhaust valve 39 is also kept closed and the check valve 40 is, on the other 75 hand, kept open.

The admission and exhaust valves 30 to 37 of the two cylinders 1 and 2 are then operated alternatively so as to distribute live steam alternatively to the two sides of the small piston, to distribute the exhaust steam of the small cylinder alternatively to the two sides of the large piston and to direct the exhaust steam of the large cylinder towards the atmosphere. The path followed by the 80 steam is then that shown on Fig. 9, as follows:

90

2. Working with full power with simultaneous admission of high pressure steam in both cylinders.

The auxiliary admission and exhaust valves 38 and 39 are kept open and the check 95 valve 40 is kept closed.

The valves 30 to 37 are operated in the same manner as before and the bifurcated path followed by the steam is then that shown on Figure 10, as follows:

100

To pass from one mode of operation to the 105 other it is thus sufficient to alter simultaneously the position of the three valves 38, 39, 40, without modifying anything to the control of the valves 30 to 37.

This result is obtained by the shifting in 110 a longitudinal direction of the non-rotatable cam member 78 (Figs. 11, 12 and 13) which is mounted in the upper part of the crank shaft and which acts on the inner ends of the pushers 48 corresponding to the valves 115 38, 39 and 40.

Finally, as to the control of the distribution valves themselves 30 to 37, it is in the present embodiment arranged in such a manner as to allow to modify gradually the 120 degree of admission in the cylinders from zero to a given maximum and to reverse the direction of the distribution by means of a simple continuous shifting of a pair of rocker-shafts 85, 86, in a manner which will 125 be further described hereafter.

To this effect the pushers 46 corresponding to the valves 30, 32 controlling the admission to and 34, 36 controlling the exhaust from the part of the small and large cylin- 130

ders respectively at the back of the piston, and the pushers 47 corresponding to the valves 31, 33 controlling the admission to and 35, 37 controlling the exhaust from the 5 part of the small and large cylinders respectively in front of the piston, are operated respectively by two series of rockers 79, 80, 81 and 82, 83, 84, oscillating freely on two parallel rocker shafts 85 and 86. These shafts 10 are mounted in the crank shaft so as to be able to slide transversely in relation to the axes of the cylinders and the valves. Each of the rockers is provided with a nose 87 adapted to push the pushers opposite which 15 it is situated, and with a roller 88 which is in contact with a camshaft 89 mounted in the crank shaft.

This camshaft 89 is operatively connected to the driving shaft 19 by means of a series 20 of gear-wheels 90, 91, 92 and 93 and has as many pairs of cams that there are rockers on each or any one of the rocker shafts 85 and 86.

Each pair of cams comprises a cam for 25 driving forward 94 and a cam for driving backward 95, which are placed on one side and the other of an intermediate cylindrical part 96 and each of which increases in eccentricity in a different direction, starting 30 from the said cylindrical or concentric portion 96.

The rockers (see Fig. 2) are all maintained between collars 97 fixed on the shafts 85 and 86 so that they have to follow the 35 longitudinal shiftings of the latter, which are obtained by operating at a distance through any suitable means a transversal piece 98 (see Figs. 2 and 11) which forms a rigid connection between these two shafts at one 40 of their ends, so that when the said piece 98 is operated, the two said shafts have to move jointly and simultaneously in a direction parallel to their own longitudinal axis, that is to say either in the direction indicated by the arrow X, or in the opposite 45 direction.

In the position shown on the drawing all the rollers 88 are on the concentric parts 96 of the camshaft so that during the rotation of the latter the rockers do not move and the valves 30 to 37 remain closed. The 50 power of the engine is then nil.

If the shafts 85 and 86 are shifted in the manner explained in the direction of the 55 arrow X (Fig. 2) the rollers 88 of the rocking levers are brought onto the parts 94 of the cams so that the rocking levers are compelled to oscillate and to operate alternatively the valves forwards and backwards, 60 which results in the engine being driven forward.

On the other hand if the shafts 85 and 86 are shifted in the opposite direction the rollers 88 come onto the cams 95 and the rocking 65 levers oscillate so as to operate the valves

in such a way that the engine is being driven backward.

It will be obvious that the power of the engine varies according to the amount of shifting of the shafts 85 and 86, as the valves 70 are lifted so much more as the rockers are acted upon by parts of increasing eccentricity of the cams 94 or 95.

As soon as the shafts 85 and 86 are moved in one direction or the other the steam is 75 thus admitted in the cylinders up to a certain degree which becomes higher as the shifting of the said shafts progresses. As the cam member 78 is at one end rigidly coupled with the shafts 85 and 86 by means of a 80 transverse piece 27 (see Fig. 11), which with the piece 98 referred to above forms a longitudinal connection between the three shafts 78, 85 and 86 so that they all have to move jointly in the direction of their longitudinal axis when either the piece 27 or the piece 98 is operated as soon as the shafts 85 and 86 are moved in any direction, the cam member 78 (Figures 11, 12 and 13) is also moved, but the cams carried thereby are so positioned that they are not brought into action until its shifting has reached a certain point, and it is only when the shifting of the shafts 85 and 86 is such that the rockers have reached a point of the cams of the 95 shaft 89 of sufficient eccentricity to allow a cut-off of about 80% that the cams of the cam member 78 begin to act on the valves 38, 39 and 40 and that the live steam arrives in the large cylinder, thus permitting 100 to obtain the maximum power of the motor.

In the embodiment illustrated and as shown in detail by Fig. 11, the means enabling the operator to vary at will and gradually the position of the longitudinally movable rocker-shafts 85, 86 and cam member 78 by shifting them jointly and simultaneously consists of a control lever 99 pivoted at 100 in a suitable bracket 101 fixed to the crank case, the said lever having its end connected 110 by means of a pivoted link 102 to the transverse piece 98 (see also Fig. 2), and the bracket 101 being provided with an integral sector shaped member 103 having a number of notches cut therein for the engagement of the usual spring pressed locking member of the lever. As the transverse piece 98 forms a rigid connection between the two rocker-shafts 85 and 86, and as one of said rocker-shafts (85 in the embodiment illustrated) is further rigidly connected to the cam member 78 by means of the piece 27, it will be readily understood that the operation of the single lever 99 will result in causing the rocker shafts 85 and 86 and the cam member 78 to move together all three jointly and simultaneously.

The means provided for shifting the rocker shafts 85, 86 and the cam member 78 may, however, take any form other than that 130

illustrated, the particular type and construction of said means being immaterial to the invention and forming no part thereof.

The noses 87 of the rockers have a sufficient length to be able to act on the respective pushers in all the positions which may be given to the shafts 85 and 86. Two of the rockers 79 and 82 operate the admission valves 30 and 31 of the small cylinder; two others, 80 and 83 operate both the exhaust valves of the small cylinder and the admission valves of the large cylinder; finally the two rockers 81 and 84 operate the exhaust valves 36 and 37 of the large cylinder.

The arrangement of the valves in several vertical and horizontal rows as shown allows their grouping in a very restricted amount of space and the arrangement of their operating mechanism in a very convenient manner. However, the arrangement of the various valves may be altered without departing from the principle of the invention with respect to the relations of the valves between them and with the cylinders, and particularly the use of the auxiliary valves 38, 39 and 40, for altering the conditions under which the engine is running.

I claim:

In a valve distribution mechanism for compound steam-engines comprising high and low pressure cylinders, the combination of a set of admission and exhaust valves, suitably guided spring-influenced valve rods for said valves, a longitudinally fixed rotary main camshaft, cams on said camshaft composed of two portions arranged to control the said valves for forward and backward drive respectively, said cams increasing progressively in eccentricity from nil to a maximum in opposite directions from their adjacent ends, a pair of longitudinally slidable rocker-shafts extending parallel to the main camshaft, a set of rockers on each rocker-shaft, having one of their ends in operative contact with the main camshaft and the other end in operative contact with the said spring-influenced valve-rod, a set of auxiliary valves for control-

ling the distribution of live steam to the admission of the low pressure cylinder and the discharge of the steam from the exhaust of the high-pressure cylinder respectively, suitably guided spring-influenced valve-rods for said auxiliary valves, a non-rotatable but longitudinally movable cam-member, extending parallel to the rocker-shafts and main camshafts and having the free ends of the last-named valve-rods bearing thereon, a rigid connection between the rocker shafts and the said non-rotative cam-member, a single operating lever, cooperating with said rigid connection, for imparting jointly and simultaneously a longitudinal movement to the pair of rocker-shafts and a corresponding longitudinal movement to the non-rotative cam-member, and a set of suitable cams on the said cam-member for operating the aforesaid auxiliary valves to admit live steam to the low-pressure cylinder and allow the discharge of the exhaust steam of the high-pressure cylinder, said cams being positioned on each side of a neutral so as to become operative only when, by the joint longitudinal movement of the respective rocker-shafts, the aforesaid rockers have reached a point of the corresponding cams of the main camshaft, on either side of said neutral, of suitably predetermined eccentricity in accordance with the fixed percentage of cut-off above which live steam should be admitted to the low-pressure cylinder, whereby the movement of the aforesaid single lever will produce at will driving in one direction and the other at any desired per cent of cut-off and automatically cause the exhaust steam of the high-pressure cylinder to be replaced by live-steam in the low-pressure cylinder when the percentage of cut-off reaches the aforesaid predetermined value substantially as described.

In testimony thereof I signed hereunto my name in the presence of two witnesses.

MAURICE BRUNET.
